UNITED STATES PATENT OFFICE.

LYMAN JOHN STARR AND WALTER HEZELTINE WHITE, OF KENOSHA, WISCONSIN,
ASSIGNORS TO THE BADGER BRASS MFG. CO., OF KENOSHA, WISCONSIN, A COR-
PORATION OF WISCONSIN.

PORTABLE LIGHT.

1,095,533.

Specification of Letters Patent.

Patented May 5, 1914.

Application filed June 3, 1913. Serial No. 771,485.

To all whom it may concern:

Be it known that we, LYMAN JOHN STARR and WALTER HEZELTINE WHITE, both citizens of the United States, residing at Kenosha, in the county of Kenosha and State of Wisconsin, have invented certain new and useful Improvements in Portable Lights, of which the following is a specification.

10 This invention relates to improvements in portable lights, and refers more specifically to improvements in the shell construction of the lamp body and reflector.

The salient object of the invention is to provide a construction in which the outer shell, the internal reflector and a front end marginal finish simulating a door are formed essentially of two sheet metal stampings.

20 Another object of the invention is to provide in such a structure extremely simple and convenient means for holding the parts reliably assembled and capable of being readily disassembled so as to afford access 25 to the space between the shells; to provide extremely simple and efficient means for so inserting the glazing and removably holding it in place as to insure a practically airtight closure, susceptible, however, of being 30 instantly opened; and in general, to dispense with the door frame structure heretofore regarded as indispensable in portable lamps of this general character, without either sacrificing the appearance, efficiency 35 or convenience of the device.

To the above ends the invention consists in the matters hereinafter described, and more particularly pointed out in the appended claims.

40 In the drawing—Figure 1 is a front elevation of a lamp embodying our invention; Fig. 2 is an axial section of the same; Fig. 3 is a sectional detail, with parts shown in perspective, showing particularly the front 45 rim construction.

The relative low cost and nevertheless structural efficiency of die-drawn sheet metal parts in portable lamp constructions is thoroughly understood in this art, it has 50 therefore been customary to make lamp body shells and door rims of sheet metal stampings.

For numerous reasons it has heretofore been regarded as essential to provide the 55 front ends of lamp bodies of the headlight type with either a removable or hinged door

frame forming a finishing front rim carrying the glazing. It is obvious that access must be had to the interior of the lamp for various reasons. Heretofore such access has 60 been provided by the front door structure mentioned. The construction and fitting of the front door of such a lamp of the headlight type represents a large proportion of the total cost of the lamp. In accordance 65 with our present invention we have adopted a structure which eliminates the necessity of a front door as such, and while providing for a perfect simulation of the conventional appearance of a door, and providing for an 70 efficient glazing seat holding the front end glazing, is nevertheless integral with the main body shell members. By such construction not only is a great saving in cost of manufacture effected but the efficiency 75 of the lamp as a structure is in no wise impaired.

Referring to the drawing, 1 designates as a whole an outer inclosing shell, 2 an internal metal reflector, and 3 the front glazing. The outer shell 1 is in the present instance of outwardly convex or semi-oval form, but it will, of course, be understood that this shape may be varied so long as the shape adopted be such that it is capable 85 of being drawn or formed from sheet metal.

In the preferred construction shown the front edge of the shell 1 is provided with an outwardly curved molding-like portion 4, integral with the main body of the shell and 90 provided near its edge with a circumferential outstanding bead 5 and approximately cylindric flange edge 6. The bead 5 constitutes a retaining and stiffening rib, and the flange 6 in conjunction with the adjacent side of the bead forms an angular seat 7 against which the other main member of the lamp fits. The reflector shell 2 is as to its main internal portion of suitable shape 95 to properly reflect forwardly the light from the filament 8 or other lighting element, being shown in the present instance as of the parabolic reflector type. At its front end this reflector shell is provided with an integral rabbet 9 to receive the edge of the 100 glazing 3 and outside and adjacent this rabbet with a radially outer bead-link portion 10, the interior 11 of which forms a retaining ring seat, and still farther outside of this with a molding-like outwardly curved 110 rim portion 2' which desirably, and as shown herein, conforms in shape to the part

4 of the outer shell and together with the latter forms an externally round molding-like finish for the front end of the lamp. The extreme edge of the part 2' is folded back upon itself, as best indicated at 12, Fig. 3, to form a bead approximately similar to the bead 5 of the outer shell member.

The manner of drawing and forming this reflector shell and its integral parts into the shape described will be readily understood by those skilled in this art, except possibly the formation of the bead 11, the interior of which forms the locking ring recess. As to this, it will be noted that it lies in a plane in rear of the plane of the extreme beaded edge of the shell, and this enables a knurling or analogous expanding tool to be operated upon the shell to form the bead 11 after the shell has otherwise been practically completed. The two main shell members thus formed are locked together by means of a surrounding locking ring 13 which is U-shaped in cross section, is provided at each end with reinforcements terminating in slightly outstanding ears 14, and held clasped around the perimeter of the lamp by means of a clamping screw 15.

The glazing 3 is held in position against its seat by means of a locking ring 16, which is desirably formed of sheet metal and of approximately semi-circular form in cross section, as best seen in Fig. 3. Preferably, instead of being truly semi-circular in cross section, its inner perimeter is flatter than a true curve and forms an obtuse angle with the face of the glass against which it rests, thereby giving to the ring the appearance of its being a continuation of the inner side of the front molding member of the lamp, and, moreover, avoiding the formation of a recess in which mud or lamp polishing compounds might lodge. The locking ring 16 is divided at one point in its circumference so that it may be inserted in place, and its two ends are bridged by a metal clamp 17 embracing the same, and secured in place by a screw-bolt inserted through the clamp, between the ends of the ring, through an aperture in the underlying seat structure and into a nut 19 soldered on the interior, as indicated clearly in Fig. 2. The peculiar configuration or cross sectional shape of the locking ring 16 is such that when expanded and locked in place its inner edge bears resiliently against the glazing, thus insuring a constantly tight joint and preventing the possibility of rattling. To still further insure a tight seal at this joint and lessen liability of breaking the glazing, an elastic rubber or analogous washer is fitted between the edge of the glazing and the seat 9, as indicated at 20, Fig. 3.

The outer shell is provided with suitable supporting lugs 21 and which in the present instance are shown as inserted outwardly

through the body of the shell and provided with internal flanges 22 which are soldered to the interior thereof.

The center of the reflector is apertured to receive the shank of an incandescent lamp bulb 8', the socket 8" of which lamp is within the space between the two shells. A connector socket 23 is mounted to extend through the outer shell at a suitable point in the rear portion thereof; the connector socket 70 and the lamp socket being connected by flexible cord connections 24 of considerable length, so that the incandescent lamp may be assembled with the reflector while the latter is removed from the body shell.

The manner of use of the device will be obvious from the foregoing description. Inasmuch as electric lamps do not require to be opened in order to turn on or off the current, it will be obvious that it will be seldom necessary to open the lamp, the occasion for so doing being either to renew or replace a bulb or adjust the focus of the latter, or possibly repair something. New glazing can obviously be replaced without separating the shells of the lamp. To replace a bulb it is necessary to remove the glazing, but this is readily accomplished by simply removing the locking ring.

While we have herein shown a preferred embodiment of the invention, it will nevertheless be understood that the details of configuration and construction may be changed without departing from the invention.

We claim as our invention:

1. In a lamp of the general character described, the combination of a drawn-metal outer shell with an integral rear end, a glazing, a drawn-metal inner shell with an integral rear end nested within said outer shell 105 and provided with a recessed seat for said glazing, means for holding said glazing in position in said seat, the front margins of said two shells being conformed to meet or substantially meet, thereby to form a finishing trim around the glazing opening, and means for detachably holding said shells together.

2. In a lamp of the general character described, the combination of a drawn-metal outer shell with integral front and rear ends, a drawn-metal reflector portion nested within said outer shell, a glazing closing the front-end opening of the lamp-body, means for detachably locking the reflector portion 115 to the front end of said outer shell, and means for locking said glazing in position and independently of the reflector locking means.

3. In a lamp of the general character described, the combination of a drawn metal outer shell with integral rear end, a drawn metal inner shell with integral rear end and nested within said outer shell, the front end margin of said inner shell having a rever-

- and outwardly drawn front end extension formed integrally with the main body of the shell, the front end margin of said outer shell and the margin of said reversely drawn extension of the inner shell being conformed to meet or substantially meet to thereby form a finishing-trim around the glazing opening, a glazing seat formed in said inner shell, a glazing seated therein, and means 10 detachably uniting said shells. 60
4. In a lamp of the general character described, the combination of a drawn metal outer shell with integral rear end, a drawn metal inner shell with integral rear end constituting a reflector, said inner shell being nested within said outer shell and being of less depth axially than the outer shell whereby a substantial shape is formed between the nested shells, an integral reversely drawn 15 molding-like extension formed upon the front end of said inner shell, an integral molding-like extension formed upon the front end of the outer shell, the edges of said molding-like extensions being conformed to meet or substantially meet in the assembled lamp to thereby form a hollow, molding-like finishing-trim around the glazing opening, a locking ring encircling and detachably connecting the meeting edges of 20 said shell members, and a glazing seated in the front end of the reflector portion of said inner shell. 70
5. In a lamp of the general character described, the combination of a drawn metal outer shell with integral rear end, a drawn metal inner shell with integral rear end and nested within said outer shell, the front end portion of said inner shell being in the form of a reversely drawn hollow molding- 25 like finishing-trim, the marginal edge of which is located at the circumferentially outer perimeter of the lamp body, the front end portion of said outer shell being conformed to meet or substantially meet the edge margin of the return portion of the inner shell, an integral rabbet-like glazing seat formed in the interior of said inner shell and located in a plane in rear of the meeting edges of the outer and inner shells, a glazing seated within said glazing seat, a locking ring detachably seated in said rabbet outside the glazing, a locking ring encircling and detachably connecting the meeting 30 edges of the shells, an incandescent lamp the lighting element whereof is within the chamber formed between the glazing and the inside of the inner shell, and the socket portion within the space between said shells, 75
- and suitable electrical connections extending from said lamp through the outer shell. 65
6. In a lamp of the general character described, the combination of an outer shell, an inner shell nested within said outer shell and provided with a recessed seat, a glazing detachably locked into the seat of the inner shell, an outer locking ring for said glazing, locking it within said seat, and means for detachably holding together the inner and outer shells. 80
7. In a lamp of the general character described, the combination of a drawn-metal outer shell with integral front and rear ends, a drawn-metal inner shell with an integral rear end and nested within said outer shell, means for detachably holding said shells 75 together, a glazing detachably locked into the open face of the lamp, and means for locking said glazing in position while said shells are locked together in operative position and controlled from the front of the 80 lamp. 85
8. In a lamp of the general character described, the combination of an outer shell, an inner shell nested within said outer shell, a glazing seated within said inner shell, a locking ring for holding said glazing in position, and a locking ring for detachably holding together the outer and inner shells. 90
9. In a lamp of the general character described, the combination of an outer shell 90 provided with a circumferential outwardly-projecting flange, an inner shell nested within said outer shell and provided with a similar flange, a glazing detachably locked into the inner shell, and means for locking together the inner and outer shells, comprising a circumferential locking ring embracing both of said flanges. 95
10. In a lamp of the general character described, the combination of a drawn-metal outer shell with integral rear end, a drawn-metal inner shell provided with a recessed seat and an integral rear end nested within said outer shell, each of said shells being provided with a circumferential outwardly-projecting flange, a locking ring embracing both of said flanges and locking said inner and outer shells together, a glazing, and means for detachably holding said glazing in position on said seat. 100 105
